United States Patent Office

Des. 213,413
Patented Feb. 25, 1969

213,413

FONT OF LETTERS FOR SIGNS

Joseph J. Marcin, Chicago, Ill., assignor to Spanjer
Brothers, Inc., Chicago, Ill., a corporation of Illinois

Filed Jan. 4, 1968, Ser. No. 10,055

Term of patent 14 years

U.S. Cl. D96—12
Int. Cl. D18—04

FIG. 2

FIG. 1 is a face view of a font of letters for signs showing my new design; and

FIG. 2 is a cross sectional view taken on line 2—2 of the letter "I" shown in FIG. 1 and is representative of the cross section of the other letters.

The backs of the letters are flat and unornamented.

I claim:

The ornamental design for a font of letters for signs, substantially as shown and described.
